UNITED STATES PATENT OFFICE.

ALBERT A. SORG, OF GRAND RAPIDS, MICHIGAN.

LADDER.

1,356,749.

Specification of Letters Patent. Patented Oct. 26, 1920.

Original application filed August 30, 1919, Serial No. 320,962. Divided and this application filed June 8, 1920. Serial No. 387,447.

To all whom it may concern:

Be it known that I, ALBERT A. SORG, a citizen of the United States, residing at Grand Rapids, in the county of Kent and 5 State of Michigan, have invented certain new and useful Improvements in Ladders, of which the following is a specification.

My invention relates to improvements in step ladders, and its objects are: first, to 10 provide a means whereby the steps may be rigidly secured to the stiles without the use of nails, &c., and, second, to provide a means whereby the steps may be readily removed from, or resecured to the stiles, thus 15 rendering it possible to ship the ladders in the "knock down" even after they have been fully assembled.

I attain these objects by the mechanism illustrated in the accompanying drawing, 20 in which Figure 1 is an elevation of a short piece of the ladder stile with a step secured thereto by one of my devices. Figs. 2 and 3 are a front, and a back elevation, respectively of the same. Fig. 4 is an edge 25 view, and Fig. 5 is a plan of the securing device detached from the ladder. Fig. 6 shows a modified form of the securing device for securing the upper step to the stiles of the extension section of my ladder. Figs. 30 7 and 8 are a front elevation, and a side elevation, respectively, of the ladder complete, and Fig. 9 is a plan of the step supporting device shown in Fig. 6.

Similar reference characters indicate similar parts throughout the several views.

In the construction of this ladder I prefer that the steps 2 be set into the stiles 1, as at c, and to secure the steps firmly to, and into the stiles I make a sheet metal bracket 40 having a bracing element 3 that is secured to the edge of the stile, as with the screws 8. Integral with these bracing elements is an arm 4 that stands at a right angle therewith and is provided with a lateral opening 45 therethrough, formed by the two semi-circular offsets 5 and 5', so located that the bolt 6 may be passed through the stile and the opening formed by the offsets 5 and 5' and bolt the bracket firmly to the stile, the 50 bracket having first been securely connected with the step, as by the rivets a, passed through the step and the holes b in the top

of the bracket. I secure the bracket, and the step to the stile by placing the nut 7 into the slot between the offsets 5 and 5', 55 and screw the bolt 6 into it, drawing it firmly into place.

The vertically adjustable extension, 1', of my ladder has but one step, proper, as shown at 2', immediately at the top of this 60 section of the ladder, and I provide a modified form of bracket for use therewith, as indicated in Figs. 6, 8 and 9, with which I form two bracing elements 3' connected by the arm 4' in such a manner that the bolt 65 6, the same as used upon the lower sections of the ladder, may be made to engage the arm 4', in like manner, and bind the brackets and steps firmly to the stiles.

This form of brackets acts a double purpose, namely, first to bind the steps to the stiles, and, second, the part 3 acts as a brace that greatly strengthens the ladder and averts the possibility of the ladder becoming rickety with the bolts 6 properly drawn. 70

All of the steps upon the upper section of the ladder, except the upper step, are simply rungs, hence require no supporting element of the class herein described and shown, hence the necessity of the modified 80 form herein given, which is designed, only, for use upon steps that are supported, laterally, at right angles with the edges of the stile.

What I claim as new in the art, is:

1. In combination with the stiles and steps of a ladder, sheet metal brackets formed with triangular end pieces adapted to be firmly secured to the stiles, an arm formed at a right angle with the side of 90 said end, means formed upon said arm for the reception of a bolt, means for securely connecting the arm with the steps, and a bolt passed through the stile and engaging the arm in such a manner as to bind the 95 step firmly to the stile.

2. In combination with the stiles and steps of a ladder, sheet metal brackets having an end arm of triangular form, an arm integral with the triangular arm and positioned at a right angle with one side of the triangular arm, said right angle arm having a slot therethrough, and offsets formed alternately in said arm at each side 100

of the slot forming a lateral opening for the passage of a bolt, and bolts engaging said arm and binding the brackets and steps firmly to the stiles of the ladder.

- 5 3. In a bracket for assembling ladders, sheet metal arms having integral cross arms provided with openings for the reception

of bolts, and means for securing said brackets firmly to the ladder steps and the brackets and steps firmly to the ladder 10 stiles.

Signed at Grand Rapids, Michigan, May 29, 1920.

ALBERT A. SORG.
